STRAND FEEDING MECHANISM FOR
KNITTING MACHINES

Robert H. Coleman, Thomasville, N. C., assignor
of one-fourth to Ragan Knitting Company,
Thomasville, N. C., a corporation of North
Carolina, and one-fourth to Maurice Mills
Company Inc., Thomasville, N. C., a corpora-
tion of North Carolina

Application November 17, 1936, Serial No. 111,309

4 Claims. (Cl. 66—125)

This invention relates to a knitting machine and more especially to means for laying in a strand in automatic knitting machines employing cylinder and dial needles.

5 In automatic seamless knitting machines employing both dial and cylinder needles, it is a well known fact that these machines are capable of knitting a welt at the top of the stocking together with a ribbed portion and a leg portion 10 together with heel, toe and foot portions, in other words, knitting a complete stocking with the exception of looping the toe after the stocking is completed on the knitting machine. Other types of dial knitting machines such as ribbed 15 inverse machines and split foot machines, knit the complete stocking except the welt.

It has been desirable to use an elastic strand in the ribbed top portion of the stocking to make a stocking which will be self-supporting and which 20 will remain in elevated position on the leg of the wearer without the necessity of employing supporters of any kind.

It has been possible to knit an elastic strand in the ribbed top portion but this takes a great 25 quantity of yarn and also greatly decreases the elasticity of the yarn on account of knitting it into the ribbed top portion under tension. It has long been desired to knit the top ribbed portion and to lay the elastic strand thereinto, but it is 30 a well known fact that an elastic strand cannot be fed into the needles at the conventional point of feeding because it would result in knitting the strand into the stocking by use of the dial and cylinder needles.

35 It is therefore, an object of this invention to provide means whereby an elastic strand can be laid in or knitted in the ribbed top portion of the stocking so that the dial needles and the cylinder needles will knit the conventional top yarn around 40 the elastic yarn without engaging the elastic yarn and knitting it in any manner at all wales at all courses.

It is another object of the invention to provide 45 in a knitting machine a strand feeding finger having means for positioning the lower end thereof immediately outside the cylinder needles and having an eye therein for feeding a strand below the latches of the cylinder needles.

It is a further object of the invention to provide 50 a strand feeding finger in knitting machines having an eyelet near its lower end through which a strand may be fed to some of the cylinder needles or below the latches thereof before they reach the throat plate of the machine, said finger having one or more cam surfaces on its

leading edge so that if the latches of the cylinder needles are not fully opened it will either open such latches or close the same and thereby prevent breakage of the irregular needles, even though it results in defective work when a latch 5 is closed by said cam surfaces.

This application is a continuation in part of my co-pending application Serial No. 757,521, filed December 14, 1934, which on November 24, 1936, became Patent No. 2,062,208.

Some of the objects of the invention having been stated, other objects will appear as the description proceeds when taken in connection with the accompanying drawings, in which:—

Figure 1 is an elevation of a portion of a knitting machine showing the cylinder and means for feeding the elastic yarn to a portion of the knitting machine so that it will be knitted by some of the needles but will not be knitted by all of the cylinder or dial needles; 15

Figure 2 is a vertical sectional view taken along line 2—2 in Figure 1;

Figure 3 is a view showing the main and pattern drums of the machine for operating the means for feeding the elastic strand to the knitting machine; 25

Figure 4 is an enlarged elevation of the lower end of the feeding finger for the elastic strand shown in cooperation with some of the cylinder needles; 30

Figure 5 is a view looking at the left-hand side of Figure 4;

Figure 6 is a top plan view of the dial cap and latch ring, showing the feed finger for the elastic strand in section; 35

Figure 7 is an elevation of the top of a stocking made in accordance with my invention;

Figure 8 is an elevation showing the manner in which the elastic strand is laid in the knitting and showing the loops in the knitting in a greatly 40 separated and distended position;

Figure 9 is a bottom plan view of Figure 8;

Figure 10 is an elevational detail showing dial and cylinder needles engaging the top yarn and showing the elastic yarn being laid in; 45

Figure 11 is a diagrammatic view looking down on Figure 10 and showing additional loops;

Figure 12 is a side elevation of the lower end of a modified form of my strand feeding finger;

Figure 13 is an edge view looking from the left 50 in Figure 12;

Figure 14 is an elevation of the lower end of another modified form of my strand feeding finger;

Figure 15 is an edge view looking from the left 55 in Figure 14.

Referring more specifically to the drawings, the numeral 10 indicates a bracket for supporting the dial needle mechanism of the machine which also supports a suitable cross-bar 11 supporting other portions of the knitting machinery. On this cross-bar there is secured a member 12 which heretofore has been provided to form guideways for a yarn feeding finger for feeding yarn to the needles at this point in case 5 of making what is called a "wrap". This comprises the member 12 having notches therein which are closed by plates 13 and 13a forming a groove in which the yarn feeding finger is adapted to have vertical sliding movement. The wrap 10 finger is dispensed with and in lieu thereof a special finger 14 is provided for feeding the elastic 15 yarn to the knitting machine so that it will not be knitted by all of the dial or cylinder needles, but may be knitted at one or two loops and laid in as 20 shown in my patent application, Serial No. 757,521, filed December 14, 1934, which matured into Patent No. 2,062,208, on November 24, 1936, or may be knitted at alternate wales and at alternate courses as set forth in my other application 25 being filed of even date herewith, Serial No. 111,308.

The member 12 not only supports the vertically sliding member 14 but also supports a tension spring 15 which normally pulls the yarn feed finger 14 downwardly. The yarn feed finger 14 has a laterally projecting pin 16 under which one arm of the bell crank lever 17 is adapted to project, said bell crank lever 17 being pivotally mounted as at 18, and having its other end connected to a link 19, which, in turn, is slidably connected to a lever 20. The lever 20 (Fig. 3) is seen to be fixedly secured to a stub arm 21 on a hub 22 mounted on a shaft 23 and fixedly secured to hub 22 is an arm 24 which is adapted 30 to follow a cam 25 on the auxiliary pattern drum 26 of the knitting machine. Lever 20a is also fixedly secured to arm 21 and is adapted to contact the main pattern drum 27 of the knitting machine and to be moved by a cam 28 thereon.

The elastic strand 30 is fed through a yarn guide 31 and downwardly just inside the latch ring 32. The yarn feed finger 14 likewise projects downwardly just inside the latch ring 32 and just outside the cylinder needles. The dial cap 33 has a dial 34a rotatably mounted therein which has a plurality of dial needles 34 and 35 mounted therein which are controlled by suitable cams not shown. The numeral 34 indicates the hook needles while 35 indicates the cast-off needles. The cylinder 36 of the machine has mounted therein a plurality of cylinder needles 37 which are of the conventional type and each has a pivoted latch 38 thereon.

The yarn feed finger 14 projects downwardly 60 immediately outside the cylinder needles and on account of the close space in which it has to work it must be provided with some means to prevent breakage of the cylinder needles. Accordingly, the lower end of the yarn feed finger has a V-shaped cam having surfaces 40 and 41 terminating in a point 42. This point 42 is slightly above the pivot points of the latches for the cylinder needles, so that it is seen that the cam surfaces 40 and 41 will serve to either open 65 or close the latches of the cylinder needles as they pass thereby, and therefore, prevent breakage of the same. This is very important. In case a latch is closed a defective stocking will be produced, but this is preferred to the breaking 70 of needles.

The lower end of the yarn feed finger 14 projects in the direction of travel of the dial and cylinder of the machine and projects downwardly and inwardly at the same time and has an eye 44 therein through which the elastic 5 strand 30 is passed so as to deliver the yarn to the needles at a point where no knitting will occur and at a point below the dial needles and below the latches of the cylinder needles so that it will not be engaged thereby and at a point where 10 the cylinder needles will likewise not engage it so that the cylinder needles will engage alternate loops on the ordinary strand and the dial needles will engage the other loops so that the strand is knitted across the elastic strand in the manner 15 shown in Figures 8 to 11 inclusive, without either the cylinder or dial needles knitting the elastic strand, except for a loop or two, but merely laying it in, in the manner shown and described.

The dial cap 33 has the conventional leaf 20 spring yarn clamp 45 thereon. It also has the conventional movable yarn clamp 46 thereon which is operated in a conventional manner. It also has conventional shears 47 thereon which is also operated in a conventional manner. The clamp 46 and the shears 47 are operated by suitable instrumentalities, not shown, controlled by the auxiliary pattern drum when the elastic strand is withdrawn from laying in position.

The dial cap has its upper surface beveled on 30 the side next to the throat plate 48 and the yarn fingers 49. In order to introduce the elastic strand at a thin place in the dial cap where it will traverse the cylinder needles, I mount a pin 50 in the dial cap to prevent the elastic strand 35 from passing over the high edge of the dial cap and being held where it will not be engaged by the hooks of the cylinder needles when it is introduced to laying in position.

In Figure 1 the elastic strand is shown after 40 it has been introduced and has passed completely around the cylinder and has passed inside the cylinder needles at the throat plate and is being laid in.

Although Figure 2 is taken along the line 2-2 45 in Figure 1, the elastic strand 30 is shown in a different position, being in the position it occupies when first lowered to a position where it will be caught by the hook of one of the cylinder needles, as it is seen that in introducing the 50 elastic strand, it is passed between two cylinder needles and being held by the spring clamp 45 the hook of a cylinder needle will carry the elastic strand around to knitting position where the end of the elastic strand is pulled from beneath the spring clamp. Although the elastic strand will be caught and knitted by one or two needles, the subsequent cylinder needles will not knit in the elastic strand for the reason that it fed at 55 a point below the latches and on top of the sinkers which will cause it to ride over the tops of the cylinder needles when they are lowered in a knitting operation.

It will be observed in Figure 3 that the pattern 60 drum 27 serves to lower the yarn feed finger when the lever 20 falls into the cavity in the cam surface, but it is also evident that this main drum cannot be used for throwing the elastic strand out of position where it will be laid into the fabric 70 because it moves too slowly and would not raise the yarn feed finger 14 quickly enough, and therefore, means are provided whereby the auxiliary pattern drum can be employed for throwing the elastic strand out of operation after a pre- 75

determined number of courses of elastic strands have been laid into the ribbed top.

Let us assume that the cavity appearing in the cam surface 28 of Figure 3, represents the length of the top of the stocking. Therefore, the auxiliary pattern drum 26 will throw the elastic strand out of operation long before the main drum 21 has moved far enough for cam 28 to engage the lever 20a and therefore the auxiliary pattern drum will throw it out of operation and not interfere with the top of the stocking.

In Figure 7, a finished top is shown as made on one type of machine in which usually a small welt W will be knitted and then the yarn feed finger 14 will be automatically lowered and the portion E will have the elastic strand laid therein, which will be withdrawn long before the top ribbed portion has been completed and the remainder of the top will be knitted of ordinary ribbed fabric by the dial and cylinder needles but without laying the elastic strand therein, although it is evident that the entire ribbed portion could have a strand either elastic or otherwise, laid therein, if desired.

It is also well understood in the art, that in knitting ribbed fabric that alternate cylinder needles are used with all of the dial needles, as there are twice as many cylinder needles as dial needles and by using half of the cylinder needles only, then the dial needles pass between the cylinder needles and engage the knitting strand between the cylinder needles thus resulting in alternate loops being engaged by the hook dial needles and the other loops are engaged by the cylinder needles.

The elastic strand is threaded through the yarn feed finger 14 and placed under the conventional clamp and in front of pin 50 and when the elastic strand finger is lowered one of the cylinder needles engages the elastic strand because from pin 50 to eye 44, it goes in front of one of the cylinder needles. This needle, and possibly another, receives the same in their hooks to be knitted in along with the top yarn at the knitting point, and then the yarn is carried around on the outside of the cylinder needles and when it reaches the throat plate, where the conventional knitting operation takes place, the conventional knitting occurs which consists of a course of the top yarn being engaged by alternate cylinder needles as only one-half of the cylinder needles are in operation during this operation and the hooked dial needles move out between the cylinder needles and engage the top yarn and pull the alternate loops back against the dial and then the alternate cylinder needles from their loops. At this point, the cylinder needles, being lowered, allow the elastic strand to pass in and rest on the loops held by the hooked dial needles. On the next revolution, the elastic strand being laid on all of the loops held by the hook dial needles for a complete revolution, the second and subsequent knitting operations take place on the second and subsequent revolutions of the knitting machine which repeats the above described operation, that is, the cylinder needles engage the top yarn and at the same time the hook dial needles and the cast-off dial needles move out and the hook dial needles engage the strand of yarn being knitted and the cast-off needles cast off the loops held by the cast-off dial needles onto the loop being formed at that time by the hooked dial needles.

It is thus seen that the elastic strand is not knitted except at its ends but is laid in between

the wales formed by the dial needles and the cylinder needles.

In Figures 8 to 11 inclusive, there is shown the manner in which the elastic strand is laid in the knitting of the ribbed top. It is seen that the cylinder needles 37 engage the top yarn t and that the dial needles 34 and 35 engage the top yarn between the loops formed by the cylinder needles, and Figure 10 shows the hook and cast-off dial needles in position where they move their loop outwardly over the laid in elastic strand to a point where the hook needles 34 will engage the next course of top yarn t and then the cast-off needle will cast off the already formed loop onto the new loop being formed by the hook dial 10 needles. This lays the elastic strand in between the wales formed by the dial needles and the wales formed by the cylinder needles. The knitting of the dial and cylinder needles is in the conventional manner, but a description of same 20 has been made in order to show how the elastic strand is laid in during this ribbing operation.

The cylinder needles form the loops c, while the dial needles form the loops d.

The latches in the needles will be entirely open 25 if the machine is operating properly by having top yarn fed thereto, and the conventional latch opener in the machine is functioning properly, and the needles are being lowered properly by the needle leveling mechanism. Now if the top 30 yarn breaks, or the needles are not leveled or lowered properly due to some imperfection of the machine, resulting in the latches not being entirely open but occupying a position below a horizontal plane passing through the pivot point of 35 the latch, then the lower cam surface 41 will complete the opening of the latches. If the latches should be projecting upwardly but not entirely closed, then of course, it is evident that they could not take the elastic strand and the 40 upper cam surface 40 would completely close these latches resulting in an imperfect knitting, but it would prevent the needles and latches of the machine from being broken.

Figures 12 and 13 show a slightly modified form 45 of feed finger 52 which has integral with the lower end thereof an outstanding projection 53 through which a suitable inclined eyelet 54 is provided. The projection 53 is disposed on the side of the finger which is farthest removed from 50 the hooks of the needles 37 in order that the finger may be operated in close proximity to the needles. The finger is also provided with an enlargement or heel 55, said heel having inclined beveled surfaces 56 and 57 which meet at a 55 common point 58. Likewise, this point is adapted to be placed at an elevation which is substantially the same as the pivot point of the latches so that any latches which might be partially opened or closed as they pass the finger, 60 will be deflected downwardly or upwardly by beveled surfaces 56 or 57.

In Figures 14 and 15, still another modified form of finger is shown, which is denoted by reference character 60. This finger has an outstanding lug 61 integral with its lower end through which an eyelet 62 is provided whose longitudinal axis is substantially parallel to the direction of travel of the cylinder needles. The projection and eyelet are disposed on the side of 70 the finger 60 which is farthest removed from the hooks of the cylinder needles 37 for the same reason as set forth in the preceding form. It is desirable, at times, to position the eyelet in this manner so that the amount of friction produced 75

as strand 30 passes through the eyelet 62 to the needles 37 will be materially reduced; however, it is not possible to deliver the strand 30 as close to the needles in this form as in the form shown in the preceding figures where the outlet of the eyelets are disposed on the side of the feed finger which is adjacent the needles. A heel 63 is provided which has arcuate surfaces or edges 64 and 65, said edges intersecting as at 10 66. This point 66 is also adapted to operate at an elevation substantially the same as that of the pivot points of the latches 38, when they pass the finger 60, so that any latches which are outstanding will be either closed or opened by 15 beveled edges 64 or 65, thereby preventing damage to the needles.

When the ribbed top of a stocking is knitted on a Scott & Williams model HH knitting machine it is customary to use alternate cylinder needles 20 and all of the dial needles. It will be noted by referring to Figure 1 that the conventional dividing cam 37b engages the butts 37a of the low needles 37 and forces these needles downwardly immediately before these needles reach the point 25 of introduction of the elastic strand 30, whereas, the alternate high needles are disposed at such an elevation that their butts 37a will pass over cam 37b. This cam will prevent the hooks of the alternate low needles from engaging the strand 30 at any time.

In the drawings and specification, there has been set forth a preferred embodiment of the invention, and although specific terms are employed, they are used in a generic and descriptive sense only, and not for purposes of limitation, the scope of the invention being set forth in the appended claims.

I claim:

1. in a knitting machine having revolving dial needles and also having cylinder needles provided with pivoted latches and also having revolving dial needles, a vertically movable yarn feed finger for feeding a strand to the outside of the cylinder needles thereof and below the latches thereof, and below a horizontal plane defined by the dial needles so that the strand will be inlaid

between the loops formed by the dial needles and the loops formed by the cylinder needles, the leading edge of the lower end of said finger having a pair of diverging cam surfaces thereon and occupying substantially the same vertical plane for 5 engaging and opening or closing the latches of any needles which are not already opened.

2. A yarn feed finger for knitting machines, provided with revolving cylinder needles having pivoted latches and also having dial needles, comprising a yarn feeding portion disposed on the outside of the cylinder needles and having an eye disposed below the latches of the needles and through which the yarn is passed to the exterior of the needles and below the latches thereof to be inlaid between the loops formed by the dial and cylinder needles, and having a cam surface in advance of and above the eye for engaging and moving the latches of any needles whose latches are not completely opened.

3. In a knitting machine having revolving cylinder needles and dial needles, and a throat plate having yarn feed fingers for feeding yarn to the needles, a strand feeding finger disposed immediately outside the cylinder needles at a point where the needles will pass the strand feeding finger before they reach the throat plate, said finger having an eye in its lower end for feeding an inlay yarn below the latches of the cylinder needles, means for lowering the strand feeding 20 finger to a point where its strand will be engaged by the hooks of some of the needles and fed below the latches of the other needles to thereby knit the strand at some needles and lay it in at the other needles.

4. In a knitting machine, a yarn feed finger disposed for vertical movement immediately outside the cylinder needles of said machine at a point in advance of the throat plate of said machine, said finger having diverging surfaces near 40 its lower end for opening or closing the latches of any needles which may have their latches partially opened, and having an eye in its lower end for feeding a strand on the outside of and below the latches of the needles.

ROBERT H. COLEMAN.
